UNITED STATES PATENT OFFICE

LOUIS H. HILDEBRANDT, OF AMSTERDAM, NEW YORK, ASSIGNOR TO COLLINS LOOM WORKS INC., OF AMSTERDAM, NEW YORK, A CORPORATION OF NEW YORK

ADJUSTABLE STOP MECHANISM FOR YARN-MEASURING SPOOL WINDERS

Application filed August 25, 1928. Serial No. 302,129.

This invention relates to winding devices, particularly those adapted to wind tuft yarn spools such as are used on Axminster looms.

The object of this invention is to provide a 5 readily adjustable stop mechanism for use on winding devices for setting frames and similar machines; a stop mechanism which will automatically stop the winding mechanism as soon as the desired length of yarns (be it the 10 length which will fill the spool, or but a fraction of that length) is wound thereon. This present invention is an improvement over the stop mechanism disclosed in United States Patent No. 1,185,633, issued June 6, 1916, to 15 Charles H. Collins, and which was designed to insure the winding of a definitely fixed amount of yarn upon each spool wound.

The manner in which I have accomplished my object is illustrated in the accompanying 20 drawings which show my improved adjustable automatic stop mechanism as associated with the measuring device disclosed in the above mentioned patent to Collins; Fig. 1 being a top plan view, and Fig. 2 a front 25 elevation, a part of the frame and one of the measuring rolls of the Collins device being shown.

Referring to the drawings, B represents a 30 usual measuring roll such as is adapted to contact with, and be driven by the longitudinal movement of the yarns as they are drawn onto the spool in any usual manner, B¹ represents the shaft of the measuring roll, and F a portion of the frame of the spool winding machine provided with measuring rolls.

2 is a stud on which is journalled a disk 3, having a notch 4 formed in the periphery thereof. To the disk 3 is secured, so as to move as a part thereof, a spur gear 5 which is 40 in mesh with a similar spur gear 6 secured on the shaft B¹ of the measuring roll B.

One end of an arm 7 is pivoted as at 8 to a 45 suitable support formed on or secured to the frame F of the spool winder and yarn measuring device, the other or free end thereof having pivoted thereto or therewith a bell-crank lever 9, the downwardly projecting short arm 10 of which is adapted at times to enter the notch 4 in the periphery of the disk 3 over which it is located.

To the end of the shaft B¹ of the measuring roll B is secured a handle 11 whereby the roll may be manually rotated when necessary or desirable.

On the shaft B¹ is secured a worm 12 engaging the worm gear 13 on the lower end of the shaft 14 which is a part of or is secured to the rotary table 15, and is journalled in a bearing block 16 pivotally mounted as at 16' to the frame F. The lower end of the shaft 14 is journalled in a shiftable bearing 17 which is normally forced toward the shaft B¹ by a spring 18 which will normally hold the worm gear 13 in operative contact with the worm 12.

The top of the table 15 is divided by regularly spaced radial graduations 20 at least a part of which are identified by suitable indicia; and on the top of this table is a pin or projection 21 adapted to strike the side of the upper end of the lever 23 which is fulcrumed at 24 to the frame F or a suitable bearing secured thereto. The lower end of the lever 23 has a side projecting part 25 adapted to slip under the arm 7 when it is raised to draw the short arm 10 of the bell-crank lever 9 free of the notch 4 in the disk 3 and from contact with the periphery thereof. The lever 23 is controlled by a spring 26 the tendency whereof is to force the lower end of the lever toward the arm 7 and the projection 25 to slip under it. A stop 27 limits the movement of the lever 23 under the urge of its controlling spring.

The outer or long arm of the bell-crank lever 9 is connected, as by a rod 30, to the stopping mechanism of the spool winder (not shown), and which it is adapted to actuate.

The operation of my adjustable stop mechanism is as follows:

The device being at rest, force is applied to withdraw the worm gear 13 from engagement with the worm 12 (in opposition to the spring 18), which will free the table or dial 15 so that it may easily be rotated counter clockwise to withdraw the projection 21 from contact with the upper end of the lever 23 for any desired distance. The graduations on the table 15 indicate the amount of yarn, in feet, which will be laid upon the spool by the spool winder during the time it is being

rotated from the "set" to the "kick off" position. For instance: in the drawing the table is illustrated as being "set" at "4", which means that four feet of yarn will be wound upon the spool before the projection 21 will travel to the "kick off" position and the zero mark be in front of the pointer 31.

After the table has been rotated backward and set at the desired point the arm 7 is raised until the projection 25 slips thereunder and so holds the arm 10 out of the notch 4 and away from the periphery of the disk 3; the worm gear is then permitted to return into engagement with the worm under the urge of the spring 18, and the shifting mechanism or clutch of the spool winder actuated to start the machine. As the spool winds on the yarns the measuring roll will be rotated and will cause the table 15 to be rotated in a clockwise direction, and just before the last of the desired length of yarn reaches the spool the pin or projection 21 on the table 15 will contact with the upper end 22 of the lever 23 and force it to rotate about its fulcrum point so as to withdraw the part 25 from under the arm 7 and permit that arm and the bell crank lever carried on the end thereof to drop, the short arm 10 of said bell crank coming into contact with the periphery of the disk 3. As the disk 3 continues its regular rotation, communicated to it from the measuring roll, the end of the arm 10 will ride the periphery of the disk 3 and eventually enter the notch 4, and just as the last of the desired length of yarn is laid upon the spool the long arm of the bell-crank lever 9 will be kicked up, due to the urge of the disk 3, in the notch 4 in which the short end has then come to rest, and so shift the starting and stopping mechanism of the spool winder to the "stop" position.

I claim:

1. An adjustable stop mechanism for a spool winding device which includes a measuring roll adapted to contact with the yarns being wound and be rotated thereby, and including: a support, a rotatable disk with a notch in the periphery thereof; means whereby the rotation of the measuring roll will cause said disk to be rotated; an arm one end thereof being pivoted to said support; a bell-crank lever pivoted to the free end of said arm, one end thereof adapted to enter the notch in said disk the other to be operatively connected to the usual starting and stopping mechanism of the spool winder; a rotatable and adjustable table journaled in suitable bearings, said table being provided with indicia and having a projection thereon; a spring controlled double armed lever pivoted to said support, one end adapted to contact with said projection, the other to be projected beneath said arm when it is raised sufficiently to free the bell crank from the notch in said disk; and means whereby each revo-

lution of the measuring roll will cause said table to be rotated a certain fractional part of a complete revolution.

2. An adjustable stop mechanism for a spool winding device which includes a measuring roll adapted to be rotated by the yarn travel, and including: a support, a rotatable disc with a notch in the periphery thereof; means whereby said disk is caused to make one revolution each time the measuring roll makes one; an arm one end thereof being pivoted to said support; a bell-crank lever pivoted to the free end of said arm, one end thereof adapted to enter the notch in said disk when brought into alignment therewith, the other to be operatively connected to the usual stopping mechanism of the spool winder; a rotatable and adjustable table journaled in suitable bearings, said table being provided with indicia and having a projection thereon; a spring controlled double armed lever pivoted to said support, one end adapted to contact with said projection, the other to be at times projected beneath said pivoted arm under the urge of its controlling spring; means whereby the starting position of the projection on said table may be changed at will; and means whereby each revolution of the measuring roll will cause said table to be rotated a certain part of one revolution.

3. An adjustable stop mechanism for a spool winder which includes a measuring roll adapted to contact with the yarns being wound and to be rotated thereby, and including: a support, a rotatable disk with a notch in the periphery thereof; means whereby each rotation of the measuring roll will cause said disk to make one rotation; an arm one end thereof being pivoted to said support; a bell crank lever pivoted to the free end of said arm, one end thereof adapted to enter the notch in said disk by gravity when brought into alignment therewith, the other to be operatively connected to the usual stopping mechanism of the spool winder; a rotatable and adjustable table journaled in suitable bearings, said table being provided with indicia and having a projection thereon; a spring controlled double armed lever pivoted to said support, one end adapted to contact with said projection, the other to be at times projected beneath said pivoted lever and under the urge of its controlling spring; the top of said table provided with regularly spaced graduations; an operative connection between said table and said measuring roll whereby the rotation of said roll will cause rotative movement of said table; and means whereby said operative connection may be broken at will and the table freed for manual adjustment.

4. An adjustable stop mechanism for a spool winding device, which includes a measuring roll adapted to be rotated by contact

with the yarn being wound, a support, a rotatable disk, means for rotating said disk incident to the rotation of said roll, an arm pivoted on said support, adjustable means for normally holding said arm in an inactive position and releasing said arm after a predetermined amount of yarn has been unwound, whereupon said arm gravitates to an active position, and means forming a connection between the arm and the starting and stopping mechanism of the spool winder, and actuated by said disk incident to the release of said arm to stop said mechanism.

5. An adjustable stop mechanism for a spool winding device which includes a measuring roll adapted to be rotated by contact with the yarn being wound, a support, a rotatable disk, means for rotating said disk incident to the rotation of said roll, an arm pivoted on said support, means normally holding said arm in an inactive position, means including an adjustable and rotatably mounted table for effecting a release of said arm after a predetermined amount of yarn 20 has been wound, allowing said arm to gravitate to its active position, means for rotating said table incident to the rotation of said roll, and means providing a connection between the arm and starting and stopping mechanism of the spool winder to automatically stop the latter as said arm assumes its active 25 position.

In testimony whereof I have affixed my signature.

35 LOUIS H. HILDEBRANDT.
